UNITED STATES PATENT OFFICE.

SAMUEL R. CAMPBELL, OF BUFFALO, NEW YORK, ASSIGNOR OF ONE-HALF
TO EDWARD MICHAEL, OF SAME PLACE.

DOOR-SECURER.

SPECIFICATION forming part of Letters Patent No. 377,927, dated February 14, 1888.

Application filed February 28, 1887. Serial No. 229,106. (No model.)

To all whom it may concern:

Be it known that I, SAMUEL R. CAMPBELL, of the city of Buffalo, in the county of Erie and State of New York, have invented a new 5 and useful Improvement in Door-Fasteners, of which the following is a specification.

This invention relates to that class of door-fasteners which are inserted under the lower edge of the door for preventing the door from 10 being opened, except, possibly, by applying considerable force, which would be liable to arouse the person occupying the room.

The object of my invention is the construction of a simple and convenient door-fastener, 15 which will hold the door securely and which can be produced at small expense.

My invention consists of the improvements which will be hereinafter fully set forth, and pointed out in the claims.

20 In the accompanying drawings, Figure 1 is a perspective view showing my improved door-fastener in position for securing a door. Fig. 2 is a sectional elevation showing my improved door-fastener in the same position. Fig. 3 is a rear elevation of the fastener. Fig. 4 is a top plan view thereof. Fig. 5 is a rear elevation of the fastener, showing the same in position ready to be inserted under the door.

Like letters of reference refer to like parts in 30 the several figures.

A represents a tapering or wedge-shaped block or plate provided, preferably in both of its edges, with serrations or teeth *a*, which are adapted to embed themselves into the adjacent 35 wooden parts. This block or plate is made of such size and form as to enter under the lower edge of doors of usual construction.

B represents a transverse bar or lever, which is movably connected with the plate A, near 40 the rear or butt end thereof, and by which the plate can be turned after it has been inserted under the door. The bar B passes loosely through an opening, *b*, in the plate A, and is provided at its ends with heads which prevent 45 it from becoming detached from the plate A.

The bar B is provided at one end with a bent portion or knee, *c*, which permits the bar to be laid closely against the plate A, as represented in Fig. 4, when the device is not required for use.

D represents a pivoted detent-pawl, which is hung to the rear end of the plate A, and which assists in preventing the plate from being moved on the floor or other surface on which it rests. The detent D is preferably 55 made U-shaped, and has its arms *d d* arranged on both sides of the plate A, the horizontal bar *d'* of the detent being journaled in an opening formed in the plate A near the rear end thereof. Each of the arms *d* of the detent is 60 preferably provided with duplex points *e* projecting in opposite directions, so that the detent can be reversed, if desired.

When the device is to be inserted under a door, the plate A is laid flat upon the floor, or 65 nearly so, as represented in Fig. 5, and inserted under the door in this position. The plate is then turned up into a vertical position by means of the lever B. This causes the teeth *a* of the plate to embed themselves into the 70 lower edge of the door and into the floor or threshold, as indicated in Fig. 2. The detent D is then arranged to resist the movement of the plate A in the direction in which the door is required to be swung for opening the same. 75 The plate A, when firmly engaged with the adjacent wooden parts, prevents the door from moving in either direction, although it offers the greater resistance to a force which tends to move the door upwardly on the inclined 80 edge of the plate. When the plate is in position under the door, the bar or lever B rests with one end on the floor and prevents the plate from being turned over. When it is desired to withdraw the plate, it is turned down 85 by means of the lever B to the position represented in Fig. 5.

My improved fastener is very simple in construction, convenient in use, and can be produced at small expense.

I claim as my invention—

1. In a door-fastener, the combination, with the tapering plate or block A, of a detent, D, hung to said plate or block, substantially as set forth.

2. In a door-fastener, the combination, with the tapering plate or block A, of a reversible detent, D, hung to said plate or block and provided with duplex points, substantially as set forth.

100

3. In a door fastener, the combination, with the tapering plate or block A, of a transverse bar or lever, B, and a detent, D, hung to said plate, substantially as set forth.
- 5 4. In a door-fastener, the combination, with the tapering serrated plate or block A, provided with an opening, b, of a transverse bar or lever, B, inserted loosely through said opening and provided at its ends with heads which to prevent the withdrawal of the lever from the

opening b, and with a bent knee, c, at one end which permits the bar to be laid closely against the plate, substantially as set forth.

Witness my hand this 29th day of January, 1887.

SAMUEL R. CAMPBELL.
